FOLDING ARTICLE OF FURNITURE

John Kovats, Fairfield, Conn.

Application April 30, 1936, Serial No. 77,112

19 Claims. (Cl. 311—82)

This invention relates to furniture of the table or like class, and to such articles of furniture having collapsible legs; the invention being of special value in regard to portable card or game tables. For convenience, any piece of furniture to which the invention is applied will hereinafter be referred to as a table.

An object of the present invention is to provide a leg-operating mechanism for a table such that in moving the legs to change the table from collapsed to extended condition, or vice versa, first one group of legs is thus moved and then another group of legs is thus moved. In this connection, preferably, the arrangement is such that, where four legs are to be collapsed or extended, the movement of a pair of diagonally opposite legs toward extended or collapsed position precedes a similar movement of the other two legs. To this end, preferably, each leg of one of these pairs is operatively connected to the other leg of its pair, so that it is merely necessary to move a single leg from extended to collapsed position in order to effect movements of another leg to such position.

A further object of the present invention is to provide an improved operating mechanism for the legs of a table, whereby such legs can all be moved from extended to collapsed or retracted position, as the result of manually moving merely any one selected leg, and according to an arrangement whereby the movement manually given to the selected leg automatically results in the giving of similar movements to the other legs, either so as to move first one group of legs and then to move another such group, or so as to move one leg after another all around the table.

A further object of the present invention is to provide operating means individual to each leg and of the general type shown and described in my copending application Serial No. 595,983, filed March 1, 1932, but of an improved type.

Still a further object is to provide operating mechanism for the legs of a table, wherein novel and valuable improvements are incorporated for collapsing the legs seriatim.

These and other objects and advantages will hereinafter be described or apparent.

In the drawings, illustrating two embodiments of the invention as at present preferred:

Figure 1 is a bottom plan view of one of said embodiments, with the legs collapsed; the same being a rectangular table having four legs one at each of the table corners.

Fig. 2 is a similar view of another embodiment applied to the same table, and one having similarly placed legs, these legs also shown collapsed.

Fig. 3 is an enlarged fragmentary view, showing various parts as seen at the upper right-hand corner of Figure 1.

Fig. 4 is a side elevation of the parts shown in bottom plan in Fig. 3, that is, looking in the direction of the arrow 4 of Fig. 3.

Fig. 5 is a view similar to Fig. 3, but showing said parts redispersed to place and hold the associated legs in extended position.

Fig. 6 is an end elevation of said parts, that is, looking in the direction of the arrow 6 in Fig. 5.

Referring to the drawings in detail, the present invention is shown as embodied in a card table, the top 10 of which includes a rectangular frame 11 carrying a central board 12, and upon which cards may be played or food may be served.

Four legs are shown at the four corners of the table top. The two of these legs which constitute a diagonally opposite pair thereof when in extended position are marked 14, and the two remaining legs, which constitute another diagonally opposite pair thereof when in extended position, are marked 15.

Referring now to the form of the invention shown in Figure 1, and in that connection referring especially to Figs. 3 to 6, each leg is coupled to the table top 10 by way of a hinge connection including a base structure 16 fixed to said top and a swingable structure secured to and mounting the inner end of one of the legs 14 and 15.

This base structure as shown comprises a sheet metal plate cut and shaped to include a long wall section 17, another somewhat shorter wall 18 at right angles to the wall section 17, and a short wall section 19 parallel to the section 17. The wall sections 17 and 18 fit flat against the inner sides of the adjacent members of the frame 11, being fastened thereto by screws 20.

The swingable structure shown, marked 21, comprises a sheet metal plate cut and shaped to include an integral barrel 22 which is just wide enough to fit between the wall sections 17 and 19 of the base structure; a pin being passed through the barrel and through holes in these two wall sections and being headed over as indicated at 23 to complete the pivotal connection between the two structures 16 and 21.

The swingable structure 21 is shown as being also provided with a channel 24 for comparatively free and easy sidewise reception of the upper or inner end of a leg 14 or 15, this channel in the present case being shaped to fit a leg of rectangular cross-section. Such leg is secured in the channel 24 by studs or rivets 25. The barrel 22 has extended outwardly from the same

a flat extension constituting a ledge 26 against which the inner end of the leg abuts and which limits upward movement of the leg in the channel 24.

- 5 In the illustrated form of the invention, a toggle interconnects each base structure 16 and the associated swingable leg-carrying structure 21. One of the side walls of the channel 24 presents an ear 27, and to this ear a toggle link 28 is pivoted at 29. Said link is pivoted at 30 to the other link 31 of the toggle, which link 31 is pivoted to wall section 17 of the base structure 16. Such pivoting of link 31 is on a boss 32 formed on said wall section 17 and by means of a rivet 33.

10 15 In order positively to limit a toggle to maximum distension, for holding the leg 14 or 15 in extended position perpendicular to the top 10, as shown in Fig. 5, as well also as to limit such toggle to maximum collapse, for holding a leg 20 in its desired collapsed position, here shown as parallel to the plane of said top 10, a double-stop means is provided which in the present case includes a pin-and-slot connection. The pin of such connection is a headed stud 34 suitably secured in place to project above a boss 32' formed on wall section 17 of the base structure and alongside the aforesaid boss 32, and the slot of such connection taking the shank of said stud 25 is an arcuate one 36 formed in toggle link 31.

30 35 In order yieldingly to urge each toggle and consequently the associated leg toward the extended position shown in Fig. 5, when such toggle and leg have been manually moved sufficiently toward such extended position to straighten out the toggle to some extent, an expansile spring 37 is provided (see particularly Fig. 5) having a central tension coil 37a, and also having at one end a terminal curl fitted and retained in a shaped edge-recess 17a forming an extension 40 of a properly cut-away portion 17b of the wall section 17 of the base structure 16; said spring being angularly bent at its other end to provide a short offset extension 37c sent through a hole in toggle link 31, such hole marked 31a in Fig. 45 3, and through a matching hole 38' in a member 38a below described. Such spring offers no appreciable resistance to moving the associated toggle and leg from extended to collapsed position, nor is it able to act expandingly of the toggle when the latter is collapsed as in Fig. 4. However, once the toggle has been so far extended from the condition shown in Fig. 4 as to move the end 37c of the spring beyond the straight line joining the effective anchorage 55 point of the curled end of the spring and the pivot 33, the tension of the spring tends to move the toggle further toward expanded condition. Thus, should the user fail to move the associated leg to fully extended position, the spring 17 acts to correct this inadvertent failure. Said spring acts, furthermore, to hold the stud 34 in one end of the slot 36 as shown in Fig. 5, and thereby insures that the pivots 29, 30 and 33 will be held in a straight line as an effective stop to prevent the leg from tilting inwardly of the table.

60 65

To fold or close any selected leg, it is merely necessary for the user to press on the associated pair of toggle links 28 and 31 near the intermediate pivot 30, and after such pivot is moved out of the straight line between the two end pivots 29 and 33, the links may be moved about the hinge connection 22-23 with ease. As the leg is swung closer and closer toward the underside of the table top there is an increasing action of

the spring 37 in urging the leg toward full collapse. The spring thus serves to facilitate movement of the leg to folded position, and tends to maintain the leg in folded position while the table is moved about and when it is stored.

Referring now to the illustrated means for effecting collapse of the legs seriatim, the member 38a above-mentioned is a leaf extension offset from what may be termed a relay means, that is, a means for relaying the collapsing movement 10 of one leg to another leg, so that the second-mentioned leg will be collapsed as the result of collapsing the first-mentioned leg. This means is here shown as in the form of a plate 38, fixed on toggle link 31 by rivets 39, and having a main portion cut-away as at 40 opposite its associated leg, to allow that leg to collapse when the associated toggle is collapsed, and beyond such cut-away extended as a laterally projected, curved wing 41, hereinafter called the relay ele- 20 ment.

As will be seen most clearly from Figures 1 and 2, the relay element 41, carried by each of the four similar toggles which on collapse thereof causes the associated leg to be folded in under the table top, is alongside that leg and is in position to be pressed downwardly to cause that leg to collapse when an adjacent leg is moved toward collapsing position. In other words, assuming, as indicated in Figs. 5 and 6, that the first collapsed leg is a leg 15, as soon as that leg moves to the dot-and-dash position shown in these views further pressure thereon in the direction of the arrow 42 exerts a pressure in the direction of the arrow 43 on the relay element 41 for an adjacent leg 14. This results in a downward pressure on the pair of toggle links shown in Figs. 5 and 6 so as to move the intermediate pivot 30 out of the straight line between the two end pivots 29 and 33, and this toggle and the leg 14 are collapsed to the condition shown in Fig. 4 as the leg 15 and its toggle are similarly collapsed.

Thus, either leg 14, or either leg 15, can be first manually collapsed, but in any case to result in the automatic collapse of all the other legs, due to the operation of the relay elements 41, serially 45

In order to provide for the manual collapse of two legs simultaneously, as those of the pair 14 or those of the pair 15, so that incidental to such collapse the remaining pair of legs will be automatically collapsed by the relay elements 41 carried by the toggles associated with the two legs last-mentioned, means are associated with each pair of diagonally opposite legs so that each such pair can be moved conjointly, either from collapsed position to extended position, or vice versa. The base structure of the hinge connection for each leg has a wall section 44 horizontally offset from its long side wall section 17, this wall section 44 lying flat against the underside of the table top. Mounted on wall section 44, by a pivot 45, is a rocker plate 46, for bell-crank action, and provided with an arcuate flange 47 cut-away to present a pair of teeth for engaging a pin 48 carried by the associated toggle link 31. As will be understood, with the associated toggle collapsed as in Fig. 4, and with the parts described arranged as there shown, said rocker plate as seen in Fig. 3 will be rotated in a clockwise direction when said toggle is expanded to extend the associated table leg; and in collapsing the leg, said plate will be rotated in a counter-clockwise direction.

Each of the four rocker plates 46 shown in Figure 1 similarly operates, incidental to a move- 75

ment of the associated leg from collapsed to expanded position, and vice versa.

As shown in Figure 1, the two rocker plates 46 respectively associated with the two diagonally opposite legs 14 are connected by a pair of links 48, each pivoted at its opposite ends to the two rocker plates as indicated at 49. Similarly, the two rocker plates 46 respectively associated with the two diagonally opposite legs 15 are connected by a pair of like links 49, each pivoted at its opposite ends to the two rocker plates as indicated at 50.

Thus, still referring to Figure 1, when either of the legs 14 is manually moved from collapsed to extended position, or vice versa, the other leg 14 moves similarly therewith, and when either of the legs 15 is so moved the other leg 15 moves therewith; due to the linkages described. And when either pair of legs 14 or 15 is thus moved from extended to collapsed condition, and by manual handling of only one of the legs of either selected pair, the other pair of legs is similarly automatically moved, due to the relay elements 41 carried by the toggles associated with the last-mentioned pair of legs. For instance, imagine the collapsed table standing upright on the floor as seen in Figure 1, but with the legs extended: then a person standing behind the table and facing toward the observer of the underside of the table, could pull in toward him, conveniently by the use of his left hand, the leg 14 hinged at the upper right-hand corner of table top, and, as the lower end of this leg swings in to engage the relay element 41 seen at the upper left in Figure 1, his right hand would be conveniently available to apply added pressure to the outer end of said leg 14 to increase the depressive force on said element 41, thus causing both legs 14 to swing into the fully collapsed position shown in Figure 1 as both legs 14 are being finally brought to that condition.

In the embodiment shown in Fig. 2, as will be noted, the means for operatively interconnecting the legs 14 and for similarly connecting the legs 15 are omitted; the base structures 16 at the four corners of the table, as here shown, having removed therefrom the wall sections 44 of Figures 1 and 3 to 6.

Nevertheless, as already pointed out, in Fig. 2 the moving of any selected leg from its expanded to its collapsed position results in automatically bringing about a collapsing of all the other legs. In this case, however, the legs are collapsed, one by one and one after another, all around the table. Should, for example, the leg 14 hinged at the upper right-hand corner of the table top in Fig. 2, be the one manually engaged for collapsing first, the free end of that leg, near the conclusion of its closing movement, engages the relay element 41 at the upper left-hand corner in Fig. 2, whereupon the leg there hinged is given a collapsing movement and near the conclusion thereof engages the relay element 41 at the lower left-hand corner, whereupon the leg there hinged begins a collapsing movement; and this last-mentioned leg near the conclusion of its collapsing movement engages the relay element 41 at the lower left-hand corner, whereupon the leg there hinged begins its collapsing movement. These four leg collapsing movements, in the embodiment described, are all completed by the respective springs 37, and all the four legs are held in collapsed position by such springs.

Variations and modifications may be made within the scope of this invention and portions

of the improvements may be used without others.

I claim:

1. In a folding table, a table top; a plurality of legs for said table top hingedly connected thereto for movements to extended and collapsed positions, each of said hinge connections being independent of the others; and means for initiating movement of one leg toward collapsed position actuated by another leg in response to the concluding movement of said other leg toward collapsed position. 10

2. In a folding table, a table top, a plurality of legs for said table top hingedly connected thereto for movements to extended and collapsed positions, each of said hinge connections being independent of the others; and means for initiating movement of one leg toward collapsed position actuated by an adjacent leg in response to movement of said adjacent leg toward collapsed position. 15

3. In a folding table, a table top; a plurality of legs for said table top movable to extended and collapsed positions; means operatively connecting each pair of diagonally opposite legs whereby the legs of each of such pairs may be 25 conjointly collapsed independently of the other of said pair; and means responsive to conclusion of the movement of one of said pairs of leg in collapsing direction for initiating a conjoint collapsing movement of the other pair of legs. 30

4. In a folding table, a table top; a plurality of legs for said table top movable to extended and collapsed positions; and means independent to each leg and operative to move said leg from extended toward collapsed position, said means 35 including a member engaged by another leg only while that leg is concluding a movement toward collapsed position.

5. In a folding table, a table top; a plurality of legs for said table top movable to extended and collapsed positions; and means independent to each leg and operative to move said leg from extended toward collapsed position, said means including a member engaged by a perimetrically adjoining leg only while that leg is concluding 40 a movement toward collapsed position. 45

6. In a folding table, a table top; a plurality of legs for said table top movable to extended and collapsed positions; independent mechanism associated with each leg and operative to move that leg from extended to collapsed position, each mechanism including an actuating means for engaging another leg, each leg being so guided in its collapsing movement that during such movement it engages one of said means associated 50 with another leg, the means last-mentioned being engaged and actuated by the leg last-mentioned substantially at the conclusion of its movement to collapsed position. 55

7. A folding table as in claim 4, wherein there 60 is means for operatively connecting the leg last-mentioned to its diagonally opposite leg for conjoint movement therewith, and wherein there is means for operatively connecting the leg first-mentioned to its diagonally opposite leg for conjoint movement therewith. 65

8. A folding table as in claim 4, wherein there is means for operatively connecting each of said legs to its diagonally opposite leg independently of the connection of its adjacent or adjoining leg. 70

9. A folding table as in claim 4, wherein the means to move a leg includes a bracing means, including a toggle, said bracing means carrying the member engaged by another leg.

10. A folding table as in claim 4, wherein 75

means are provided for automatically urging a leg toward fully collapsed position when such leg is partially moved toward such position.

11. In a folding table, a table top; a plurality 5 of legs for said table top movable to extended and collapsed positions; and means operative to move a leg from extended toward collapsed position, said means including a bracing means for each leg and a relay element operatively connected to said bracing means, and said leg-moving means being rendered operative when the relay element is actuated by another leg while that leg is being moved toward collapsed position, such engagement occurring after the last-mentioned leg has partially completed such a movement.

12. In a folding table, a table top; a plurality 10 of legs for said table top, movable to extended and collapsed positions; and means operative to move a leg from extended toward collapsed position, said means including a toggle connecting each leg with the table top and a relay element 15 operatively connected to said toggle, and said leg-moving means being rendered operative when the relay element is actuated by another leg while that leg is being moved toward collapsed position, such engagement occurring after the last-mentioned leg has partially completed such a movement.

13. In a collapsible table, the combination, with 20 a top and collapsible legs, of a mounting for each leg including a hinge connection between the top and the leg; a toggle collapsed when the leg is collapsed and extended to place its pivots substantially in a straight line when the leg is extended; a spring acting to urge said toggle toward extended condition or collapsed position when the toggle is moved predeterminedly toward extended or collapsed condition; double-acting stop means for holding the toggle in fully extended or fully collapsed condition; a rocker element 25 engaging said toggle, and rocked in one direction when the toggle is moved to extended position and rocked in the opposite direction when the toggle is moved to collapsed position; and means associated with the toggle and engageable by an adjacent leg when that leg is moved toward collapsed position for breaking the toggle whereby the leg controlled by said toggle moves to collapsed position.

14. In a collapsible table, the combination, 30 with a top and collapsible legs, of a mounting for each leg including a hinge connection between the top and the leg; actuating means for

each leg, including a relay element operatively associated with the table and movable to collapse said leg when the latter is extended; said relay element, when said leg is extended, being positioned to be engaged by the free end of another leg while that leg is being collapsed.

15. A table, as in claim 14, wherein said relay element is a rockable plate.

16. A table as in claim 14, wherein said relay element is a rockable plate having a field of operation through a plane at an angle to the plane of operation of the leg engaging it.

17. A table as in claim 14, wherein said relay element is a rockable plate having a field of operation through a plane at an angle to the plane of operation of the leg engaging it, there being a collapsible bracing means for the leg operated by the plate, and said relay element being secured to said bracing means.

18. In a folding table, a table top; a plurality 20 of legs for said table top movable to extended and collapsed positions; means operative to move a leg from extended toward collapsed position, said means including a bracing means for each leg and a relay element operatively connected 25 to said bracing means; and said leg-moving means being rendered operative when the relay element is actuated by another leg while that leg is being moved toward collapsed position, such engagement occurring after the last-mentioned 30 leg has partially completed such a movement; and means for automatically urging a leg toward fully collapsed position when such leg is partially moved toward said position.

19. In a folding table, a table top; a plurality 35 of legs for said table top movable to extended and collapsed positions; means operative to move a leg from extended toward collapsed position, said means including a bracing means for each leg and a relay element operatively connected 40 to said bracing means, and said leg-moving means being rendered operative when the relay element is actuated by another leg while that leg is being moved toward collapsed position, such engagement occurring after the last-mentioned 45 leg has partially completed such a movement; means for operatively connecting each of said legs to its diagonally opposite leg; and means for automatically urging a leg toward fully collapsed position when such leg is partially moved toward 50 said position.

JOHN KOVATS.

CERTIFICATE OF CORRECTION.

Patent No. 2,128,465.

August 30, 1938.

JOHN KOVATS.

It is hereby certified that error appears in the printed specification of the above numbered patent requiring correction as follows: Page 3, second column, line 19, claim 2, before "movement" insert the words a concluding; line 27, claim 3, for "pair" read pairs; line 28, same claim, for "leg" read legs; and that the said Letters Patent should be read with this correction therein that the same may conform to the record of the case in the Patent Office.

Signed and sealed this 1st day of November, A. D. 1938.

Henry Van Arsdale
